Primary Examiner—Wallace R. Burke

Assistant Examiner—Horace B. Fay

[57] CLAIM

The ornamental design for a crank handle, as shown and described.

DESCRIPTION

FIG. 1 is a front, top and right side perspective view of a crank handle showing my new design;

FIG. 2 is a rear, top and left side perspective view thereof;

FIG. 3 is a left side elevational view thereof, the side opposite being a mirror image thereof;

FIGS. 4 and 5 are respectively front and rear elevational views thereof; and

FIGS. 6 and 7 are respectively top and bottom plan views thereof.
